UNITED STATES PATENT OFFICE

2,670,548

LAUNDRY DRYING APPARATUS

Monte F. Huebsch, Norwood, Ohio, assignor to
The American Laundry Machinery Company,
Norwood, Ohio, a corporation of Ohio

Application October 13, 1952, Serial No. 314,439

2 Claims. (Cl. 34—127)

1

The invention relates to laundry drying apparatus.

The object of the invention is to provide an improvement in laundry drying apparatus of the type having a plurality of drying tumblers and a single heater and a single exhaust means such as shown in my prior U. S. Patent No. 2,351,429, dated June 13, 1944, for Drying Apparatus. The improvements over said prior patent comprise a duct system for conducting the heated air to each of the drying drums and the offsetting of the axis of these drums relative to each other and the center line of the housing so as to provide an inlet conduit for the lower drum and an exit conduit for the upper drum with only a slight increase in width of the casing over that of my prior patent. With this arrangement each of the drums gets its own supply of heated air which makes for quicker drying and considerable floor space is saved over known arrangements.

A further object of the invention is to provide a single damper in connection with the structure above described whereby the heated air may be directed to both drums or diverted or partially diverted from one of the drums and thus control the supply of heated air furnished to the drums.

This application is a continuation in part of my copending application Serial No. 269,160, filed January 31, 1952, for Laundry Drying Apparatus, now abandoned.

The invention further consists in the several features hereinafter set forth and more particularly defined by claims at the conclusion hereof.

In the drawings:

Fig. 1 is a front elevation view of laundry drying apparatus embodying the invention, parts being broken away and parts being shown in section;

Fig. 2 is a detailed front elevation view of a portion of the upper end of the casing;

Fig. 3 is a side elevation view of the apparatus, parts being broken away and parts being shown in section;

Fig. 4 is a detailed diagrammatic view of the drum drive.

Referring to the drawings, the numeral 5 designates an upright casing having a heater compartment 6 provided with steam heated coils 7 over which the drying air is drawn through an opening 8 in the casing and discharged through an apertured bottom plate 9 provided with an opening 10.

The casing has a top drum 12 and a lower drum 13 mounted therein. These drums and their

2

mountings may be of any suitable form but are preferably similar to the drum and drum mounting of the prior U. S. Patent No. 2,048,743, dated July 28, 1936, to myself and P. M. Pearson. As shown, the drums are of sheet metal having a plurality of apertures 15, a flanged opening 16 in one end, lifting ribs 17, and a shaft mounting 18 at the other end to which a shaft 19 is secured. As in the above mentioned Patents Nos. 10 2,351,429 and 2,048,743, access to each drum is through a door 20 hinged at one side to the casing and normally covering a flanged opening 21 in the casing aligned with but slightly smaller than the opening 16 in each drum. Each door 15 is held in normally closed position by a latch pivoted on the door and engageable with a keeper on the casing as shown in said patents.

Referring to Fig. 1, the shaft mounting 18 for the drum 12 is offset from the center line of the 20 casing and to the right so that the periphery of this drum comes close to the adjacent side casing wall 5a, and the drum 13 is offset from the center line of the casing and to the left so that its periphery comes close to the adjacent side 25 casing wall 5b.

A series of baffles or partitions are arranged in the housing and cooperate with the walls thereof to form separate heat supply and exit passages to the drums 12 and 13. In Fig. 1, an S-shaped 30 partition 22 extends from the damper herein-after described down around the left side of the drum 12 and then down around the right side of the drum 13 and cooperates with the plate 9, the damper, and the wall 5b to provide a separate inlet conduit 23 for the drum 13 and also cooperates with the plate 9, the damper, and side wall 5a to provide a separate inlet conduit 24 for the drum 12 leading from the opening 11, and it also cooperates with said side wall 5a to provide an exit or exhaust conduit 25 for the drum 12. The conduit 25 may be streamlined at its lower end by the curved partition 26, and there may also be a partition 27 extending inwardly from the wall 5b to provide a more restricted discharge opening 28 for the drum 13. The partitions 26 and 27 are not essential.

The exhaust from the conduit 25 and from the drum 13 is conducted into a common exhaust chamber 29 in which an exhaust fan 30 is mounted which acts to discharge the spent heated air to atmosphere, and at the inlet to the housing for this fan I prefer to mount my lint remover which includes a perforated drum 31 mounted and arranged as more particularly 50 shown and described in my U. S. Patent No. 55

2,611,192, dated September 23, 1952, for Lint Remover for Driers.

The drive shaft 32 for the fan 30 is directly connected to the shaft of an electric motor 33 which carries a pulley 34 connected by a belt 35 with a pulley 36 which forms a part of a speed reduction mechanism 37 whose output shaft 38 carries a sprocket 39. A sprocket 40 is mounted on the shaft 19 for each drum. A chain 41 meshes with both of the sprockets 40, the sprocket 39 and the sprocket 42 of a chain tensioner, so that both drums 12 and 13 are driven by the motor 33 when the fan 30 is operating and heat is being supplied to the coils 7.

For controlling the supply of heated air to either drum, the single opening 10 in the bottom plate 9 of the heater compartment 6 has a damper member 43 cooperating therewith. Member 43 is a plate secured at its lower edge to a transversely extending rod 44 pivotally mounted at its ends in the opposite sides of the casing 13 at the upper end of the S-shaped partition 22 and having its front exteriorly disposed end 45 provided with an operating handle or crank 46 which may have an index pointer 47 cooperating with an indicator scale 48 as shown in Fig. 2. As shown in Fig. 1, when the damper 43 is in mid-position, it divides the space defined by the opening 10 into passages 49 and 50 so that heated air from the compartment 6 is directed into the space or conduit 24 to supply heated air to the drum 12 and also into the inlet conduit or space 23 to the drum 13 to supply heated air thereto. The air for the drum 12 after passing therethrough is carried down through the conduit 25 to the exhaust chamber 29 and then passes through the lint remover to the fan 30 and from thence to atmosphere, and the air for drum 13 after passing therethrough is exhausted through the opening 28 to the chamber 29 and then passes through the lint remover to the fan 30 and from thence to atmosphere. Thus each drum gets its quota of fresh air and exhausts its spent air through separate conduits without increasing the overall width of the housing or casing more than the width of one of these conduits. Moving the damper 43 toward the right, as viewed in Fig. 1, will decrease or shut off the supply of heated air furnished the drum 12, and moving it toward the left will decrease or shut off the supply of heated air furnished the drum 13. Thus the heated air supply to one of the drums may be cut off or reduced while the other drum receives its full supply of heated air. It will be noted that the damper 43 forms a movable partition portion of the partition 22.

I desire it to be understood that this invention is not to be limited to any particular form or arrangement of parts except in so far as such limitations are included in the claims.

What I claim as my invention is:

1. In a laundry drying apparatus, the combination of a casing having upper and lower perforated drying drums revolvably mounted therein,

an air heater at the top of said casing, conduit means between said heater and said drums for separately conducting heated air to the upper portion of each of said drums, the upper drum being offset laterally to a position adjacent one side wall of the housing, the lower drum being offset laterally to a position adjacent the opposite side wall of the housing, said conduit means including a wall member extending between said drums, the offsetting of these drums, the said side walls of the housing and the wall member extending between said drums providing housing portions for said drums and an inlet conduit for the lower drum extending down at one side of the upper drum and an exhaust conduit for the upper drum extending down on the opposite side of the lower drum, the housing portion of said lower drum having an outlet, a common exhaust chamber for the spent air from said drums communicating with the outlet from said lower drum and the lower end of said exhaust conduit, and an exhaust fan communicating with said exhaust chamber.

2. In a laundry drying apparatus, the combination of a casing having upper and lower perforated drying drums revolvably mounted therein, an air heater at the top of said casing having an outlet, the upper drum being offset laterally to a position adjacent one side wall of the housing, the lower drum being offset laterally to a position adjacent the opposite side wall of the housing, an S-shaped partition extending between said drums, a damper forming a movable upper part of said partition and working between the sides of said outlet to control the flow of air from said heater to either of said drums, the offsetting of said drums, the side walls of said housing together with said partition extending between said drums providing housing portions for said drums and an inlet conduit for the lower drum extending down at one side of the upper drum and an exhaust conduit for the upper drum extending down on the opposite side of the lower drum, the housing portion for the lower drum having an outlet, a common exhaust chamber for the spent air from said drums communicating with the outlet from said lower drum and the lower end of said exhaust conduit, and an exhaust fan communicating with said exhaust chamber.

MONTE F. HUEBSCH.
